tion of Iowa

Application April 10, 1953, Serial No. 348,004

3 Claims. (Cl. 323—45)

This invention relates in general to electronic alternating current voltage regulators and in particular to a voltage regulator which operates with a saturated tube.

Since power is proportional to the root-mean-square of an alternating voltage rather than to its peak value or average value, it is oftentimes particularly desirable that an alternating voltage be regulated by its root-mean-square value rather than its peak or average value. Root-mean-square voltage regulation is particularly useful when furnishing a voltage for the filaments of vacuum tubes. A filament requires constant power to maintain a constant temperature and variations in peak or average voltages are immaterial as long as the power remains constant.

An example of an alternating voltage regulator which regulates by average voltage value rather than root-mean-square voltage value is a circuit which rectifies a sample output and regulates the alternating output to maintain the rectified sample at a constant voltage. It is therefore the principal object of this invention to provide a voltage which is regulated so as to obtain a constant root-mean-square value.

Both alternating and direct current voltage sources have been used at various times to heat tube filaments. Oftentimes in direct current systems there is no available separate source for the low voltage that is ordinarily required for filament heating. Therefore a large dropping resistor is required which causes large power losses and thereby inefficient power distribution.

Alternating current may be used more efficiently for filament heating because a low voltage may be obtained by transformation without the power dissipation that is unavoidable in a direct current circuit. It is therefore another object of this invention to provide a filament heating circuit which operates at high efficiency.

This invention comprises a regulator which has a diode that has its filament connected across the circuit output. The diode, which is operated at saturation, produces a plate current that is proportional to the root-mean-square of the output voltage. The diode's plate current controls the bias for the grid of a triode which acts as a variable resistor in a phase shift circuit. The phase shift circuit controls the current output of a pair of thyatrons operated in push-pull. The thyatron output is transformed by an output transformer to furnish the desired regulated voltage.

Other objects, features and advantages of this invention will become apparent to those skilled in the art from the following specification and drawings, in which:

Figure 1 is a schematic diagram of this invention; and

Figure 2 shows the vector relationships among various currents and voltages in the circuit.

Now referring to the invention in more detail, Figure 1 shows an input transformer T_1 which has a primary 10 and a secondary 11 with a grounded center tap 12 which divides secondary 11 into two equal parts 13 and 14. A first coil 16 of an output transformer T_2 has one side connected to part 13 and its other side connected to the plate 17 of a thyatron tube V_1 . A second coil 18 of transformer T_2 has one end connected to part 14 and its other end connected to the plate 19 of a second thyatron tube V_2 .

A control transformer T_3 has a secondary 22 with a grounded center tap 23 which divides it into equal parts

2

24 and 26. Part 24 is connected to the control grid 31 of tube V_1 and part 26 is connected to control grid 32 of tube V_2 . The cathodes 33 and 34 of thyatrons V_1 and V_2 are grounded.

5 One side of the primary 27 of transformer T_3 is connected to the plate 36 of a triode V_3 and its other side is connected to a B plus power supply, and to a cathode 37 of tube V_3 through resistor R_1 . Cathode 37 is connected to ground through a biasing resistor R_2 . A capacitor C_1 is connected between plate 36 of tube V_3 and part 14 of transformer T_1 by lead 35.

The grid 38 of tube V_3 is connected to the plate 41 of a diode connected pentode V_4 . A load resistor R_4 is connected between plate 41 and a B plus supply, and a 15 grounded filament 42 is connected across the circuit output terminals 29 and 30 through a limiting resistor R_5 and a potentiometer R_6 with a tap 39.

The basis for operation of this invention is the sensitivity of plate current of a saturated diode to changes in 20 filament heating power. This sensitivity is used to control the output of a thyatron circuit which then produces a constant root-mean-square alternating voltage. The saturated condition of the diode prevents variations in B plus voltage from affecting the current output of 25 the diode which thereby makes it sensitive only to changes in filament power.

To operate the circuit, an alternating current power source, which might be a 115 volt alternating current source, is connected across primary 10 of transformer 30 T_1 to terminals 15 and 20. This induces equal and opposite voltages E_1 and E_2 in secondary parts 13 and 14 which furnish the plate voltages for thyatrons V_1 and V_2 , respectively. Voltage E_2 also appears across the circuit consisting of capacitor C_1 and tube V_3 in parallel 35 with primary 27 and resistor R_1 , and grounded resistor R_2 .

Voltage E_2 will cause an alternating current I to flow through capacitor C_1 which will divide into a larger part I_1 which flows through tube V_3 and a much smaller part 40 I_2 which flows through primary 27. The tube V_3 appears as a substantially resistive impedance to current I_1 . Primary 27 furnishes a substantially resistive impedance to current I_2 because the plate resistance of V_3 is lower than the reactance of primary 27. Therefore 45 currents I , I_1 and I_2 will all be substantially in phase as shown in Figure 2.

The voltage E_c across capacitor C_1 will lag current I by substantially ninety degrees, and the voltage E_b across resistor R_2 will be in phase with current I . Since the 50 tube V_3 is essentially a resistance, the voltage E_p across tube V_3 will be in phase with current I_1 and will also be in phase with currents I and I_2 . The vectorial sum of voltages E_b , E_p and E_c is E_2 which is shown vectorially in Figure 2.

55 As current I_2 passes through primary 27, it induces equal and opposite voltages E_3 and E_4 in the respective secondary parts 24 and 26 of control transformer T_3 which are in quadrature with current I_2 and thereby are in quadrature with voltages E_1 and E_2 . The voltage 60 E_4 is the control grid voltage for thyatron V_2 and it will lag the voltage E_2 which is the plate voltage of the thyatron V_2 , by the phase angle ϕ_2 . Likewise, the voltage E_3 , which has the opposite phase of voltage E_4 , is the control grid voltage for thyatron V_1 . It will lag plate voltage E_1 which is opposite in phase from voltage E_2 , by an angle ϕ_1 , and that must be equal to the angle ϕ_2 , as will be seen in Figure 2.

The plate resistance of tube V_3 will vary with its grid 65 bias voltage E_d . The grid voltage E_d which is the plate voltage of tube V_4 will, in turn, change with the plate current of saturated diode V_4 . The output current of a saturated diode is primarily a function of the power

absorbed by its filament which in turn is a function of the root-mean-square filament voltage E_f . The output voltage E_d of diode V_4 will then be a function of the root-mean-square voltage E_f across filament 42, and since voltage E_f proportionally varies with the root-mean-square output voltage E_o across terminals 29 and 30, the bias voltage E_d must then vary with the root-mean-square voltage E_o . When the voltage E_d changes, the plate resistance of tube V_3 correspondingly changes to vary the relative lengths of the vectors E_c , E_p and E_b in Figure 2 which cause the phase angles ϕ_1 and ϕ_2 to alter the thyratron output in such direction as to oppose the initial change in voltage E_o to maintain it constant.

The resistor R_5 and potentiometer R_6 are merely used to limit the current through the filament 42 so it will operate in its saturated state, but they do not disturb the proportionality between root-mean-square output voltage E_o and filament voltage E_f . A small directly heated pentode connected as a diode has been used for tube V_4 to minimize the time constant of the regulator. The directly heated filament type of tube will follow changes more rapidly than the cathode type. It is to be understood that any type of tube operated as a diode may be substituted for the pentode shown.

For example, suppose the output voltage E_o increases, then filament 42 will become hotter thus causing an increased current to flow through tube V_4 . Since tube V_4 and resistor R_4 are connected in series between ground and B plus, an increase in current will cause the voltage of plate 41 to decrease. This decreases the bias on grid 38 of tube V_3 which results in a phase shift in the thyratron control circuits so as to decrease E_o . Thus, E_o will remain constant. A similar effect is observed when E_o becomes smaller and it will be increased to the desired value by the action of the circuit.

It is then seen that the plate currents of thyratrons V_1 and V_2 will be regulated according to the root-mean-square output voltage E_o of the circuit. Since the thyratrons provide the current through primary coils 16 and 18 which induce the output voltage in the secondary 21 of output transformer T_2 , the regulation of the output voltage is obtained by regulating the thyratron plate current. The constant value of output voltage E_o which is induced in secondary 21, can be made any desired value by suitable choice of turns ratio and by adjusting contact 39.

Although this invention has been described with respect to a particular embodiment thereof, it is not to be so limited as changes and modifications may be made therein which are within the full intended scope of the invention, as defined by the appended claims.

I claim:

1. Means for regulating an output voltage comprising, an output terminal, an output transformer with its secondary connected between ground and the output terminal, a pair of primaries of said output transformer, a pair of thyratron control tubes with cathodes connected to ground, the primaries of said output transformer connected on one side of to the plates of said thyratrons respectively, an input transformer with its primary connected to an alternating input voltage, the center tap of the secondary of said input transformer connected to ground, one end of the secondary of said input transformer connected to the other side of one of the primaries of said output transformer, the other end of the secondary of the input transformer connected to the other side of the second primary of the output transformer, a control transformer with the midpoint of its secondary connected to ground and opposite ends thereof connected to control grids of the first and second thyratron tubes, a phase shift circuit comprising a condenser and triode tube operating as a variable resistor connected in series between one end of the secondary of the input transformer and ground, the primary of the control transformer connected in the plate circuit of said triode tube, a B plus voltage connected to said control primary, a resistor connected in

series with said B plus voltage, a pentode connected as a diode connected between said resistor and ground, the plate of said pentode connected diode tube connected to the control grid of said triode tube, a potentiometer connected to the output terminal, and an output from said potentiometer supplied to the filament of said pentode connected diode tube to operate it in a saturated state.

2. Means for regulating the power of an alternating output voltage comprising, a pair of thyratron control tubes with their cathodes connected to ground, an input transformer with its primary connected to an alternating input voltage, a center tap of the secondary of said input transformer connected to ground, an output transformer with a pair of primaries connected on one of their sides to the respective plates of the thyratron control tubes and connected on their other sides to the ends of the input secondary, a pair of output terminals, the secondary of said output transformer connected between the output terminals, a vacuum tube connected as a diode with its filament connected serially to said output voltage, a direct plate voltage supply, a resistor connected between the plate of said diode and said plate voltage supply, said plate voltage adjusted to saturate said diode, a phase shift circuit comprising a condenser and a triode tube and a cathode resistor connected serially between one side of said input secondary and ground, the grid of said triode tube connected to the plate of said diode, a control transformer, a circuit comprising a resistor and said control transformer primary connected serially between the plate and cathode and cathode of said triode tube, the plate voltage supply connected in the plate circuit of said triode, the ends of the control transformer secondary connected to the control grids of said thyratron tubes, and the center tap of the control transformer secondary connected to ground.

3. Means for regulating the power of an alternating output voltage comprising, an input transformer with its primary connected to an alternating input voltage, the midpoint of the secondary of said input transformer connected to ground, an output transformer with a pair of primaries and a secondary, a pair of gas control tubes with grounded cathodes and screen grids, the plates of said gas tubes connected to opposite ends of the pair of primaries of said output transformer, the other ends of said pair of primaries connected to the respective ends of said input secondary, the secondary of said output transformer connected between an output terminal and ground, a vacuum tube connected as a diode operating in a saturated condition with its filament connected serially across the output terminals, a first resistor connected in series with the plate of said diode connected tube and to a B plus plate voltage source, a phase shift circuit comprising a condenser and a second vacuum tube with at least one grid connected serially between ground and one side of said input secondary, the control grid of said second vacuum tube connected to the plate of said diode connected tube, a control transformer with one side of its primary connected to the plate of said vacuum tube and the other side of the primary connected to the B plus supply voltage, a resistor connected between the other end of said control primary and the cathode of said second vacuum tube, the center tap of the secondary of said control transformer connected to ground, and the opposite ends of the secondary of said control transformer connected to the control grids of the first and second gas tubes.
